UNITED STATES PATENT OFFICE.

LEWIS H. FALLEY, OF KANSAS CITY, MISSOURI.

ORE-SEPARATING APPARATUS.

1,322,487.

Specification of Letters Patent. Patented Nov. 18, 1919.

Application filed April 7, 1919. Serial No. 288,401.

To all whom it may concern:

Be it known that I, LEWIS H. FALLEY, a citizen of the United States, residing at Kansas City, in the county of Jackson, State 5 of Missouri, have invented certain new and useful Improvements in Ore-Separating Apparatus, of which the following is a complete specification.

The present invention relates to apparatus 10 for the treatment of ore-carrying material, and aims to provide an improved ore separating structure whereby various ores may be recovered from rock, sand and other gangue material.

Accordingly one of the objects of the invention is to provide an improved settling 15 conduit apparatus so constructed and arranged as to effect a novel means of control of the water flow to the influence of which 20 the ore-carrying material is subjected, whereby several distinct separations of the ore are obtained in an effective manner.

For this purpose I have devised a multiple 25 conduit structure comprising several settling compartments, one within the other, and communicating through continuous passageways extending practically throughout the course of the water flow, together with a novel arrangement of deflecting elements for 30 modifying the action and direction of the water flow in order that the required separation of the ores may be effected at the points desired.

It is also sought to devise not only a practical and efficient apparatus of the character 35 described, but one that is comparatively simple and durable, having no mechanically moving parts, and which will be cheap for manufacturing and installing purposes.

With these general objects in view, the 40 invention will now be described with reference to the accompanying drawings illustrating a practical form of construction which has been devised for embodying the proposed 45 improvements, after which the novel features of the same will be set forth in the appended claims.

In the drawings—

Figure 1 is a side elevation, partly in section, showing an ore treating apparatus constructed in accordance with the present invention;

Fig. 2 is a plan view of the same;

Fig. 3 is an enlarged vertical sectional 55 view of a portion of the apparatus, the outer

conduit being in section and the inner structure appearing in elevation with a portion of each of the inner conduit members cut away for the purpose of disclosing a portion of each of the inner elements of the structure; and

Fig. 4 is an enlarged transverse section taken on the line 4—4 of Fig. 1.

Referring now to the drawings in detail, these illustrate the improved apparatus as 65 comprising an outer conduit 6 provided at its upper end with a feed hopper 8 into which the ore-carrying material is discharged, said hopper having an inclined bottom and feeding into the conduit 6 through 70 a series of openings 10, as shown in Fig. 1. At its lower end the conduit 6 is fitted with an elbow casting 12 which is equipped with a water supply pipe 14 provided with a regulating valve 16, while the said casting has 75 connected thereto, at the side opposite from said pipe 14, an ore discharge pipe 18 provided with a valve 20. The pipe 14 is to be connected with any suitable source of water-pressure supply (not shown). Arranged 80 centrally within the casting 12 is a tubular member 22 having a valve 24 and projecting up into the conduit 6 above the level of the inlet from said water supply pipe 14, said tubular member 22 being adapted to receive 85 the second ore separation as hereinafter explained.

Arranged centrally within the conduit member 6 is a second conduit 26 of smaller diameter and formed with a spiral opening 90 28 extending substantially its full length. From both edges of this opening 28 project a series of relatively small deflecting elements or fingers 29 of more or less twisted form and extending at more or less of an 95 angle across the annular space between the conduits. This arrangement of the conduits and the deflecting fingers 29 is such as to produce a mild spiral movement of the water as it is forced upward from the supply pipe 14, and at the same time impart a cross wash 100 of the water away from the inner face of the conduit 6 toward and through the opening 28 into the inner conduit 26. Such a conduit as the member 26 is conveniently 105 constructed by simply slitting the side margins of an elongated metal strip and shaping the fingers thus formed and then coiling the strip to the required shape and diameter.

Within the conduit 26 is centrally ar- 110

ranged a third conduit member 30 of still smaller diameter and formed with a spiral opening 32 and deflecting elements or fingers 34 somewhat similar to the construction of the conduit 26, but the arrangement of the opening 32 being spirally opposite to that of the opening 28 for the purpose of counteracting the upward tendency of the water flow in the annular space between the 10 conduits 26 and 30 and producing here a zone where a partial reversal of the water flow is established. In some cases I may also provide this conduit 30 with a plain spiral tubular lining 36 which is formed 15 with a spiral opening 38, said lining being coiled in a direction opposite to that of the opening 32 and thereby partially closing the passage through said opening.

Inside the conduit 30 and its lining member 36 I locate a tubular member 40 of still smaller diameter occupying an axial position within the conduit 6. This tubular member 40 is formed with a spiral opening 42 extending in the same spiral direction 25 as the openings 28 and 38, one of the edges of said opening 42 being provided with deflecting elements or fingers 44, the arrangement being such as to promote or accelerate the upward spiral movement of the 30 water through this central zone or core of the apparatus.

In the operation of the apparatus, ore-carrying material is fed into the same from the hopper 8 through the plurality of openings 10, while a continuous flow of water from the supply pipe 14 is maintained in a general upward direction through the conduit 6. This ascending water flow meets the downward precipitation of the ore-carrying 35 material, and the arrangement of the deflecting fingers 29 is such as to not only agitate the resultant mixture and produce a mild spiral twist of the water flow, but also to impart a cross wash current in the direction 40 of the opening 28. By means of this action the heaviest ore particles constituting the first ore separation are allowed to descend to the bottom of the first or outer settling compartment, *i. e.*, the space between the conduits 6 and 26, where they may be drawn off 45 through the pipe 18, while the relatively lighter ores are carried on with the water flow into the second compartment formed by the annular space between the conduits 50 26 and 30. Here the spiral arrangement of the deflecting structure is such as to produce an opposite twisting effect upon the water flow and establish a zone in which the water 55 is almost stationary or partially reversed in the direction of its movement; in this way a second ore separation is effected of intermediate sizes of the ore particles, which are allowed to settle into the ore-receiving member 22, while the relatively lighter particles 60 65 are diverted by the lateral water currents

through the openings 32 and 38 into the third compartment occupied by the spiral tubular member 40. Here less resistance is interposed to the movement of the water and its upward flow is accordingly accelerated, 70 although broken somewhat by the baffle fingers 44, thereby allowing further separation of some of the ore particles within this compartment, which particles are permitted to be discharged at the lower end of the compartment into the ore-receiving member 22; the rest of the ore product, comprising the lightest and finest ore particles, is carried on out into the upper end of the conduit 6 and discharged by way of the spout 46, constituting the final separation made by the operation of the apparatus.

By means of the described construction, I have devised an improved apparatus for the separation of the finer particles of a mill 85 crush of mine dirt from the coarser particles, which is an important step in the general practice of ore concentration. The apparatus is also applicable for the removal of pollutions or impurities contained in the 90 various ore concentrates after the same have passed through the various steps of concentration, the large percentage of such impurities being contained in the finer particles. Accordingly a modification of the arrangement of this apparatus can be used to advantage as various units in the process 95 of concentrating various ores. The regulation as to the size of the separations to be made is definitely effected and controlled by 100 the amount of water supplied at the lower end of the apparatus. A sufficiently strong stream can be supplied to throw or remove, by the action of the cross wash currents, all 105 of the mill feed or ore-carrying material from the first or outer settling compartment to the middle compartment between the conduits 26 and 36,—but by diminishing the strength or force of the water flow only such of the finer material is removed from 110 the outer compartment as is desired, the coarser particles being allowed to settle to the bottom of said compartment. With regard to the various deflecting elements or 115 fingers, the number and size of these and their particular contour and angular positions are determined by the size and capacity of the machine as well as the character of the material being handled; for example, for certain classes of ores, such as 120 the heavier grades, the said deflecting fingers may be required to be set at more of an outward and downward slant than for lighter ores which are handled more effectively with the deflecting fingers arranged in 125 approximately the manner illustrated. The exact adjustment for the most efficient results is ascertained by actual operative tests with reference to the grade of ore being handled.

While I have illustrated and described what I now regard as constituting the preferred form of embodiment of the improvements I desire to reserve the right to make 5 such formal changes or modifications as may fairly fall within the scope of the appended claims.

Having described the invention, what I claim is:

- 10 1. An ore treating apparatus comprising an ore settling conduit provided with means for maintaining a flow of water therethrough, means for feeding ore-carrying material to said conduit adjacent one end 15 thereof, a second settling conduit arranged centrally within said first conduit and formed with an opening affording communication with said first conduit throughout substantially the entire length of said second conduit, and means arranged to effect a cross wash of the water away from the inner face of said first conduit toward and through said opening into the second conduit.
- 25 2. An ore treating apparatus comprising an ore settling conduit provided with means for maintaining a flow of water therethrough, means for feeding ore-carrying material to said conduit adjacent one end 30 thereof, a second settling conduit arranged centrally within said first conduit and formed with a spiral opening extending substantially its entire length and affording communication with said first conduit, and 35 means arranged to effect a spiral movement of the water around said second conduit and operating to impart a cross wash of the water away from the inner face of said first conduit toward and through said opening 40 into the second conduit.
3. An ore treating apparatus comprising an ore settling conduit provided with means for maintaining a flow of water therethrough, means for feeding ore-carrying material to said conduit adjacent one end 45 thereof, a second settling conduit arranged centrally within said first conduit and formed with a spiral opening extending substantially its entire length and affording 50 communication with said first conduit, said second conduit being provided with deflecting elements extending outward from both edges of said opening in position to impart a cross wash of the water away from the inner face of said first conduit toward and through said opening into the second conduit.
- 55 4. An ore treating apparatus comprising an ore settling conduit provided with means for maintaining a flow of water therethrough, means for feeding ore-carrying material to said conduit adjacent one end thereof, a second settling conduit arranged centrally within said first conduit and 60 formed with an opening affording communica-

cation with said first conduit throughout substantially the entire length of said second conduit, means arranged to effect a cross wash of the water away from the inner face of said first conduit toward and through 70 said opening into the second conduit, and separate discharge outlets for carrying off the separated ore products from the lower ends of said conduits.

5. An ore treating apparatus comprising 75 an ore settling conduit provided with a water inlet connection at its lower end for maintaining an upward flow of water through the conduit, means for feeding ore-carrying material to the upper end portion 80 of said conduit, a second ore settling conduit arranged centrally within said first conduit and formed with an opening affording communication with said first conduit throughout substantially the entire length of said 85 second conduit, means arranged to effect a cross wash of the water away from the inner face of said first conduit toward and through said opening into the second conduit, and a plain tubular member of approximately the 90 diameter of said second conduit and communicating therewith at a point above the level of said water inlet connection.

6. An ore treating apparatus comprising 95 an ore settling conduit provided with means for maintaining a flow of water therethrough, means for feeding ore-carrying material to said conduit adjacent one end thereof, a second settling conduit arranged centrally within said first conduit and 100 formed with a spiral opening extending substantially its entire length and affording communication with said first conduit, said second conduit being provided with deflecting elements extending outward from both 105 edges of said opening in position to impart a cross wash of the water away from the inner face of said first conduit toward and through said opening into the second conduit, and means arranged within said second conduit to retard the upward movement of the water therein.

7. An ore treating apparatus comprising 110 an ore settling conduit provided with means for maintaining a flow of water therethrough, means for feeding ore-carrying material to said conduit adjacent one end thereof, additional conduits arranged one within the other and coaxially with said first conduit and provided with spiral openings extending substantially their entire 115 length and affording communication with each other and with said first conduit, said openings extending in spirally opposite directions and provided with deflecting elements extending outward from both edges of said openings in position to impart a cross wash of the water inwardly toward and through said openings, and separate 120 discharge outlets for carrying off the sepa-

130

rated ore products from the first conduit and from the lower ends of the other conduits.

8. An ore treating apparatus comprising
5 an ore settling conduit provided with means
for maintaining a flow of water there-
through, means for feeding ore-carrying
material to said conduit adjacent one end
thereof, additional conduits arranged one
10 within the other and coaxially with said
first conduit and provided with spiral open-
ings extending substantially their entire
length and affording communication with
each other and with said first conduit, said
15 openings extending in spirally opposite di-
rections and provided with deflecting ele-
ments extending outward from both edges of
said openings in position to impart a
cross wash of the water inwardly toward
20 and through said openings, and a tubular
member fitting within the inner one of said
additional conduits and provided with a
spiral opening extending in a direction op-
posite to that of the opening of said inner
25 conduit for restricting the passage through
said last named opening.

9. An ore treating apparatus comprising
an ore settling conduit provided with means
for maintaining a flow of water there-

through, means for feeding ore-carrying 30
material to said conduit adjacent one end
thereof, additional conduits arranged one
within the other and coaxially with said
first conduit and provided with spiral open-
ings extending substantially their entire 35
length and affording communication with
each other and with said first conduit, said
openings extending in spirally opposite di-
rections and provided with deflecting ele-
ments extending outward from both edges 40
of said openings in position to impart a
cross wash of the water inwardly toward
and through said openings, a still smaller
tubular member arranged axially within the
inner one of said additional conduits and 45
formed with a spiral opening extending in
a direction opposite to that of the opening
of said inner conduit and provided with
outwardly extending deflecting fingers for
breaking up and retarding the flow of water 50
within said inner conduit and deflecting a
portion of such water into said axial tubu-
lar member, and a discharge outlet from
said first conduit approximately opposite
the upper ends of said inner conduits. 55

In witness whereof I affix my signature.

LEWIS H. FALLEY.
